Des. 205,959
Patented Oct. 11, 1966

205,959

DISHWASHING MACHINE

Thomas R. Smith, Newton, Iowa, assignor to The Maytag
Company, Newton, Iowa, a corporation of Iowa

Filed Mar. 1, 1965, Ser. No. 84,024

Term of patent 14 years

(Cl. D49—1)

Fig. 1

Fig. 2

Fig. 3

FIGURE 1 is a perspective view of a dishwashing machine embodying my new design;

FIGURE 2 is a top plan view of the dishwashing machine shown in FIGURE 1; and,

FIGURE 3 is a front elevational view of the dishwashing machine of FIGURE 1.

The rear not shown is substantially flat and unornamented.

I claim:

The ornamental design for a dishwashing machine, substantially as shown and described.
